UNITED STATES PATENT OFFICE.

ARTHUR G. HAWKES, OF DETROIT, MICHIGAN, ASSIGNOR TO AMERICAN CAR AND FOUNDRY MOTORS COMPANY, OF NEW YORK, N. Y., A CORPORATION OF DELAWARE.

BUS ROOF OR THE LIKE.

Application filed November 24, 1926. Serial No. 150,474.

The present invention relates to roof construction, and is more particularly adapted and advantageous for motor vehicle roofs, such as bus roofs especially. An aim of the 5 invention is to make the roof amply strong and stiff, and to prevent it from sagging over doors or the like, where unusually large intervals between supports may be necessary. Other objects and advantages that can be 10 realized through the invention will appear from the description hereinafter of a selected and preferred form of embodiment.

In said drawings:

Fig. 1 is a plan view of a motor bus roof 15 frame conveniently embodying the present invention, portions being broken out and omitted to bring the illustration within the limits of the paper, and only a minor portion of the roof covering being shown;

20 Fig. 2 shows a vertical longitudinal section through the roof, both covering and frame appearing in section as indicated by the line 2-2 in Fig. 1,—the figure being shortened by omission of intermediate portions;

Fig. 3 shows a transverse section through one side of the roof, taken as indicated by the line 3-3 in Fig. 1, on a larger scale;

25 Fig. 4 shows a longitudinal section through a portion of the front end of the roof, taken as indicated by the line 4-4 in Fig. 1, on a larger scale;

Fig. 5 shows a longitudinal section 30 through a portion of the roof at the rear, similar to the corresponding portion of Fig. 2, but on a larger scale;

Fig. 6 shows the end of a carline and its attachment to the subjacent frame, as seen from the exterior of the bus;

40 Fig. 7 is a fragmentary plan view of a portion of a side plate, illustrating the attachment of a side post thereto; and

Fig. 8 shows a cross section through one 45 of the carlines and its filler, with a portion of the roof covering secured thereto.

The drawings illustrate the application of this invention in connection with what is known in the art as a "Haskelite one piece roof," which for present purposes may be 50 briefly described as comprising a covering 9 (consisting of laminations of wood covered by an outer layer of textile fabric) on a substantially unitary frame structure composed of wooden wall plates (side and end plates) 10, 10, 11, and 12, and metal car-

lines 13 of channel cross section spanned between the side plates 10, 10 and provided with wooden fillers 14 secured therein by bolts 15. The laminated wood portion of covering 9 may be secured to the fillers 60 14 by nails or screws 16, as shown in Figs. 5 and 8, after which the fabric, or "mule hide" as it is called in the trade, is properly secured to the Haskelite. As shown in Figs. 1, 3, and 5, furring strips 17 extend from 65 carline to carline along either side of the roof, and also along its rear end. The carlines 13 may be concealed by a ceiling lining 18 of suitable material secured to their lower sides, with its margins gained into 70 the upper sides of wooden retaining strips 19 secured to the furring strips 17. Advertising matter or a suitable finish 20 is shown with its edges engaged behind the rounded outer edges of the retaining strips 75 19 and behind the like edge of retaining strips 21 secured to the wall plates 10, 10, and 12.

In order to make the roof frame strong and stiff, the ends of the carlines 13 are 80 preferably secured to the side plates 10, 10 substantially as shown in Figs. 1, 2, 3 and 6: that is to say, by flattening their flanges out into the plane of their webs, and by bending the flat terminal ears 22 thus 85 formed outwardly across the side plates 10, 10 and downwardly against their outer sides,—into which they may preferably be gained as shown in Figs. 3 and 6. The horizontal portion of each ear 22 may be 90 secured against the upper surface of the wall plate 10 by the strap bolts 23, 23 by which the wall plate is secured to the side posts or pillars 24, and its vertical outer end may be secured against the outer side 95 of the wall plate by horizontal bolts 25 extending between the pairs of bolts 23, 23. As shown in Figs. 6 and 7, each of the posts 24 may have a tenon 25a on its end, fitting into a corresponding vertical hole in the 100 plate 10.

As shown in Figs. 1, 2, 3, 4 and 5, the roof is stiffened as against sagging, or other vertical deformation, and also against horizontal deformation, by marginal angle plates 105 26 (as they may be termed) extending adjacent the junction between the roof and the wall, at least throughout those portions where special strength is desirable. That is to say, in the present instance, the angle 110

plates 26 extend along the sides and around the ends of the roof in both its front and rear portions, throughout the regions where the doors are commonly located. As shown in Fig. 3, each of the angle plates 26 has a depending vertical flange 27 gained into the wall plates 10, and 12, and secured thereto by the bolts 25, and along the plates 10 has a laterally extending upward sloping flange 28 that lies against the marginal or outer ends of the carlines 13 and is secured to them by bolts 29 through their fillers 14. These plates not only strengthen the roof margin against sagging or other deformation, but also strengthen it against horizontal deformation. In the roof ends, while the vertical flange 27 is bolted fast to the wall plates 11, 12 by bolts 25^b and 25 respectively, as above described, its lateral flange 28 is not secured to other parts.

At the front of the bus, the end carline 13 is connected to the corresponding overhanging front end plate 11 by a couple of metal tie bolts 30, whose outer ends are flattened and secured by bolts 31 to a wide timber 32 whose near portion forms the front end plate 11. The inner ends of the ties 30 extend through the carline 13 and have nuts 34 threaded on them at its inner side. At the rear of the bus, wooden quadrant-curved members 35 extend from the end carline 13 to the top of the rear end plate 12, to which they are secured by angle brackets 36 and bolts 37, 38 and the furring strip 17 extending across at the rear end of the roof is interrupted at the curved members 35.

While the preferred form of the invention has been shown and described, it is to be understood that the invention is not limited to the exact details of construction shown and described, as it is obvious that various modifications thereof within the

scope of the claims will occur to persons skilled in the art.

What is claimed is:

1. A roof of the character described comprising side and end plates, carlines carried by said side plates and continuous marginal angle plates extending across the ends and part way along the sides, said angle plates having flanges secured to said side and end plates and flanges secured to carlines at a distance from said end plates. 45

2. A roof of the character described comprising side and end plates, carlines carried by said side plates and a continuous angle plate extending across the end plate and part way along the side plates, said angle plate having a vertical flange secured to said side and end plates and an inwardly projecting flange secured to said carlines. 55

3. In a roof of the character described having wall plates, the corresponding roof margin, and the marginal carline ends secured directly to the wall plates, means for reinforcing the roof to prevent vertical and horizontal deformation comprising a continuous angle plate extending across an end and partly along both sides and overlapping the wall plates and the carline ends and secured to both. 65

4. In a roof of the character described, the combination with the wall plates and the corresponding roof margin directly secured thereto, of an angle plate arranged adjacent the junction of the roof margin and wall plates and extending across an end and partly along both sides, said angle plate having an upright flange by which it is secured to the wall plates and a lateral flange secured to the roof margin. 75

In witness whereof I have hereunto set my hand.

ARTHUR G. HAWKES.
